UNITED STATES PATENT OFFICE.

CHARLOTTE SAYERS, OF SYRACUSE, NEW YORK.

HOSE-SUPPORTER.

1,022,267.

Specification of Letters Patent.

Patented Apr. 2, 1912.

Application filed May 24, 1910. Serial No. 563,157.

To all whom it may concern:

Be it known that I, CHARLOTTE SAYERS, a citizen of the United States, residing at Syracuse, in the county of Onondaga and 5 State of New York, have invented new and useful Improvements in Hose-Supporters, of which the following is a specification.

This invention relates to attachments for stockings and has particular reference to 10 an attachment adapted to be engaged by a hose supporter when the stocking is on the limb of the wearer.

The object is the provision of an improved form of button to receive the band and engage with the hose supporter.

With this and other objects in view, which will more fully hereinafter appear, the present invention consists in certain novel details of construction and arrangement of parts hereinafter fully described, 20 illustrated in the accompanying drawings, and more particularly pointed out in the appended claim; it being understood that various changes in the form, proportion, size 25 and minor details of the device may be made, within the scope of the appended claim, without departing from the spirit or sacrificing any of the advantages of the invention.

30 In the accompanying drawings, forming a part of the specification: Figure 1 is a perspective view illustrating the stocking equipped with my improved device showing the position of the stocking on the limb 35 of the wearer and in engagement with the hose supporter. Fig. 2 is a longitudinal section taken through a portion of the band and stocking and also showing the button in section and its position on the band. Fig. 40 3 is a detail perspective of the button.

Similar numerals of reference are employed to designate corresponding parts throughout.

The stocking is designated by the numeral 45 5 and secured to the outer face of the stocking and adjacent to the upper end thereof is a band 6 preferably of textile material. By reference to the drawings, it will be seen that the band is secured at intervals by lon-

gitudinal and transverse rows of stitching 50 designated by the numeral 7.

The button forming part of the subject matter of the present invention is shown to include in its construction a shank portion 8, one end of which is provided with an 55 enlarged rounded head 9 and the opposite end of which is provided with an enlarged rounded back or base 10 and on either side of the shank 8 are a pair of transverse openings 11 and 12, the axis of said openings extending parallel with the axis of the shank 8, and formed in the shank 8 and adjacent to the base or back 10 is a transverse opening 13. Inclining outwardly from the back or base 10 and located between the shank 60 and openings 11 and 12 are a pair of tangs or spurs 14 and 15, the free ends of said tangs or spurs overlying the openings 11 and 12.

The buttons are arranged between the 70 stitched portions of the band, the latter being trained upwardly to one of the openings in the back or base, thence through the transverse opening in the shank and downwardly to the opposite opening in the back or base, 75 and when so trained it will be evident that the tangs or spurs 14 and 15 will embed themselves into the band, whereby movement of the button upon the band will be positively prevented. It will be evident 80 when a plurality of these buttons are secured in the manner just described and engage with the tabs of an ordinary hose supporter, that the pull exerted by the latter will be equally distributed throughout the 85 band and stocking, thus obviating the usual necessity of connecting the hose supporting tabs directly with the stocking, whereby tearing of the stocking will be prevented. The portion of the band 6 that bears against 90 the tangs or spurs 14 and 15, which serve as stops for the band, acts as a restraining element for the garment loop which engages the shank; taking the place of textile mountings, now commonly employed on garment buttons.

From the foregoing, it will be seen that I have provided an exceedingly simple device

which may be applied to most forms of stockings now in use without materially increasing the cost thereof.

I claim:

- 5   A garment supporting device consisting of a shank having heads on its opposite ends, one of said heads being formed with slots located on the opposite sides of said shank to receive a textile band and provided with
10 prongs projecting in opposite directions and

adapted to engage said textile band and the shank being formed with a passage extending therethrough and having its terminals arranged adjacent to the slots of said head.

In testimony whereof I affix my signature 15 in presence of two witnesses.

CHARLOTTE SAYERS.

Witnesses:

BESSIE M. SEELY,
JOHN H. WALRATH.
